ROTARY PUMP

Kenneth R. Pike, Hartford, Wis., assignor to West Bend Aluminum Co., West Bend, Wis., a corporation of Wisconsin

Filed June 12, 1959, Ser. No. 819,879
1 Claim. (Cl. 103—117)

This invention relates to rotary pumps and more particularly to rotary pumps having impellers of resilient material adapted for use in cooling systems of outboard motors.

Pumps of this type include a casing with a substantially cylindrical chamber therein having an inlet and outlet to such chamber. An impeller of resilient material having a plurality of deflectable radially extending vanes is rotatably mounted in the chamber. The circumferential wall is at a varying distance from the axis of the impeller. When the impeller is rotated to operate the pump, the opposite faces and vanes of the impeller wipe against the end and circumferential walls of the chamber, respectively, causing scoring of such walls when sand and other foreign material becomes lodged between the impeller and the walls.

It is the object of this invention to provide a simple, relatively inexpensive means for eliminating or substantially reducing scoring of the chamber walls to thereby prolong the life of the pump.

This is accomplished by providing grooves or depressions in the surfaces forming wiping edges against which the impeller slides which serve to wipe any sand or foreign material from the impeller and resuspend the material in the fluid. A passageway through which the sand particles can be flushed into the fluid moving through the pump may be provided. The grooves for wiping the end faces of the impeller are preferably formed by a plurality of openings in a pair of plates which cooperate with the pump housing to form the end walls of the cylindrical chamber in which the impeller is rotatably mounted. The circumferential wall of the chamber can also be provided with a suitable groove to wipe the edges of the impeller vanes in much the same manner as the apertured end plates wipe the end faces of the impeller.

Other objects and advantages will be pointed out in, or be apparent from the specification and claim, as will obvious modifications of the two embodiments shown in the drawings, in which:

FIG. 1 is a view in side elevation of the lower portion of an outboard motor (with a part of the motor leg broken away) on which a pump embodying my invention is installed;

FIG. 2 is a horizontal sectional view taken along line 2—2 of FIG. 1;

FIGS. 3 and 4 are vertical sectional views taken along lines 3—3 and 4—4 of FIG. 2, respectively;

FIGS. 5, 6 and 7 are horizontal sectional views taken along lines 5—5, 6—6 and 7—7 of FIG. 4, respectively; and

FIGS. 8 and 9 are horizontal sectional views similar to FIGS. 5 and 7, respectively, showing a second embodiment of my invention.

While this invention is particularly adapted for pumps used in outboard motor cooling systems, it should be understood that its usefulness is not limited to such applications.

Referring to the drawings, FIG. 1 shows the lower portion of an outboard motor of conventional design including a propeller 10 rotatably mounted in a lower gear housing 12 attached to an upper gear housing 14. A pump 16 which forms the subject matter of this invention is mounted on the top wall 18 of upper gear housing

2

14 inside the lower end of a motor leg 20. Pump 16 and propeller 10 are driven by a drive shaft 22 from an engine (not shown) mounted on motor leg 20.

As shown in FIGS. 2, 3 and 4, pump 16 includes a housing 24 and a back plate 26 mounted together on inner column 27 of the upper gear housing by machine screws 28 threaded into wall 18. Housing 24 has a substantially cylindrical pump chamber 30 therein having circumferential side wall 32 and opposite end walls formed by back plate 26 and a top plate 34 fitted inside chamber 30 of the pump housing.

Drive shaft 22 is rotatably mounted in column 27 and extends through housing 24 and plates 26 and 34. To prevent leakage the shaft may be provided with a packing seal 38 mounted in column 27 as shown. An impeller 40 of resilient material such as rubber or plastic is mounted on shaft 22 for rotation within pump chamber 30 by means of a hub 42 and a pin 44 (FIG. 6). Impeller 40 comprises a main body portion 46 formed around and adhered to hub 42 and a plurality of deflectable radially extending vanes 48 formed integrally with body 46. Shaft 22 and impeller 40 are not centered within the wall 32 of chamber 30. Thus, as shaft 22 is rotated vanes 48 are flexed in a conventional manner to pump water from an inlet tube 50 to a line 55 through suitable openings in plates 26 and 34 and an outlet port 52 formed in top of pump housing 24 (FIG. 4). Thus, it is seen that when sand particles become lodged between the rotating impeller and the chamber walls, damage will result if some means is not provided to wipe the sand from the mating surfaces and flush it back into the water moving through the pump.

This is accomplished by providing a plurality of depressions or openings in back and top plates 26 and 34, respectively, which not only serve to pass water to and from chamber 30 but also serve to provide an edge for wiping sand from the impeller and a passageway for flushing it back into the moving water. FIGS. 8 and 9 show the preferred embodiment of my invention wherein back plate 26 (FIG. 9) has a plurality of angularly spaced openings 54, 56 and 58 and top plate 34 (FIG. 8) has an angularly spaced opening 60 and a notch 62. The openings in the plates shown in FIGS. 8 and 9 are so arranged that when taken together they extend radially all the way from the hub 42 to wall 32 of chamber 30 so that the entire surface of the impeller will be subjected to their wiping action. The openings are angularly spaced from each other to maintain the structural integrity of the plates. Thus, it is seen that when impeller 40 is rotated clockwise (as shown by the arrow in FIG. 6) one end surface thereof will be wiped by edges 54a, 56a and 58a of openings 54, 56 and 58, respectively, in plate 26 (FIG. 9) and the other end surface will be wiped by edges 60a and 62a of opening 60 and notch 62, respectively, in plate 34 (FIG. 8).

The plate openings can be laid out in a great variety of different arrangements. A second embodiment of my invention is shown in FIGS. 5, 6 and 7 wherein plate 26 has openings 64, 66 with edges 64a, 66a, respectively, arranged as shown in FIG. 7 and plate 34 has an opening 68 and a notch 70 with edges 68a, 70a, respectively, arranged as shown in FIG. 5. It is noted that openings 64 and 66 (FIG. 7) do not, when taken together, extend the entire radial distance from hub to cylindrical wall as is the case with the other plates shown. This arrangement does, of course, provide some of the desired wiping and flushing action but to a lesser extent than that of the preferred embodiment (FIGS. 8 and 9).

As clearly shown in FIG. 5, for example, the opening 68 with wiping edge 68a for wiping body portion 46 of impeller 40 extends radially outwardly from body 46

and thus forms a passageway through which sand wiped from the body is flushed back into the water moving through the pump.

To completely wipe all surfaces of the impeller, means for wiping the edges of impeller vanes 48 which slide against wall 32 are provided. In the particular pump construction shown in the drawings, an edge 74 formed at the bumped-out portion 76 of the housing which communicates with outlet port 52 serves to wipe any sand or other foreign material from between the edges of the impeller vanes and chamber wall 32. It should be understood that if a different outlet arrangement were employed wherein, for example, no outlet portion 76 was used, a suitable wiping edge could be provided by a groove in wall 32 extending from one end wall of the pump chamber to the other.

Although two embodiments of the present invention have been illustrated and described, it will be apparent to those skilled in the art that various changes and modifications may be made therein without departing from the spirit of the invention or from the scope of the appended claim.

I claim:

In a rotary pump, a housing having a substantially cylindrical cavity therein, a first metal stamping fitted in said cavity, a second metal stamping mounted on said housing over said cavity, said first and second stampings forming the end walls of a substantially cylindrical pump chamber with the wall of said cavity forming the side wall of said pump chamber, an inlet port and an outlet port communicating with said chamber, an impeller having a plurality of flexible and resilient vanes rotatably mounted in said chamber and adapted to pump fluid from said inlet port to said outlet port when rotated, means for rotating said impeller, said impeller having opposite end face areas which rotate in contact with said first and second stampings, said vanes having peripheral edges

which wipe against said side wall of the pump chamber, a plurality of cut-out portions in each of said end stampings providing edges for wiping sand and other foreign material from said impeller, said wiping edges extending radially across said entire end face areas of said impeller, at least one cut-out portion in each stamping communicating with said inlet and outlet ports to allow liquid to flow to and from said pump chamber through said end stampings, and at least one depression in the side wall of said chamber forming a wiping edge to wipe sand and other foreign material from the peripheral edges of said impeller vanes.
